UNITED STATES PATENT OFFICE.

JOSEPH OSSOLA, OF BARRE, VERMONT.

DESIGN FOR A MONUMENT.

SPECIFICATION forming part of Design No. 31,543, dated September 19, 1899.

Application filed August 8, 1899. Serial No. 726,593. Term of patent 7 years.

To all whom it may concern:

Be it known that I, JOSEPH OSSOLA, a citizen of the United States, residing at Barre, in the county of Washington and State of Vermont, have invented and produced a new and original Design for a Monument, of which the following is a specification, reference being had to the accompanying drawing, forming a part thereof, which represents a perspective view of a monument embodying the features of my design.

The leading feature of the design consists in a monument having thereon the representation of a fractured plant and a worm at the point of fracture.

The minor features of the design consist in the broken upper side and face outlines of the monument, which convey the idea of a roughly-hewn stone, a smooth panel upon a face of the monument, and a foliate field for the aforesaid leading feature.

I claim—

The design for a monument herein shown and described.

JOSEPH OSSOLA.
